US00D816136S

(12) **United States Design Patent** (10) **Patent No.:** **US D816,136 S**
(45) **Date of Patent:** **** Apr. 24, 2018**

(54) **GEAR**

(71) Applicant: **DEKA Products Limited Partnership**,
Manchester, NH (US)

(72) Inventors: **Daniel S. Karol**, Southborough, MA
(US); **William D. Hunt**, Gilman, NH (US); **Jason M. Overton**, Manchester, NH (US)

(73) Assignee: **DEKA PRODUCTS LIMITED
PARTNERSHIP**, Manchester, NH (US)

(**) Term: **15 Years**

(21) Appl. No.: **29/572,416**

(22) Filed: **Jul. 27, 2016**

(51) LOC (11) Cl. **15-99**

(52) U.S. Cl.

USPC **D15/148**

(58) **Field of Classification Search**

(57) **CLAIM**

The ornamental design of a gear, as shown and described.

DESCRIPTION

FIG. 1 is a front, top, right side perspective view of the gear, showing our new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
